(57) CLAIM

The ornamental design for the carrying case, as shown and described.

DESCRIPTION

FIG. 1 is a perspective view of the carrying case in accordance with my new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a left side elevation view showing the carrying case with the flap open; and,

FIG. 9 is a front elevation view of the carrying case with the flap open.

The broken lines representing stitching are part of the claimed design.

The contrasting shading shown on the drawings represents cloth and Velcro® material.
